UNITED STATES PATENT OFFICE.

WILLIAM R. WHITE, OF LOUDON, TENNESSEE.

ADJUSTABLE GUIDE-COLLAR FOR SHAPER-MACHINES.

1,400,472.

Specification of Letters Patent. Patented Dec. 13, 1921.

Application filed February 21, 1921. Serial No. 446,650.

To all whom it may concern:

Be it known that I, WILLIAM R. WHITE, a citizen of the United States, residing at Loudon, in the county of Loudon, and State 5 of Tennessee, have invented certain new and useful Improvements in Adjustable Guide-Collars for Shaper Machines, of which the following is a specification.

This invention relates to improvements in 10 wood shaping machines.

The primary object of the invention is the provision of a work guiding collar for use in connection with a wood shaping machine, and which collar is independent 15 of and adjustably mounted with respect to the shaper head of said machine, thus doing away to a great extent with undue friction and vibration incident to guiding a piece of work directly against a cutter head, and 20 which frequently results in imperfect and uneven work.

A further object of the invention is the provision of a guide collar of the above described character, which is mounted upon 25 the shaping machine in such manner as to give a plurality of horizontal and vertical adjustments, to take care of wear upon the several parts of the machine, as well as to meet the requirements of accurate and 30 exacting work.

A further object of the invention is the provision of an adjustable collar of the above described character, which is simple, very durably constructed, and one which can 35 be effectively applied to standard shaping machines with very little alteration to the machine itself.

Other objects and advantages will be apparent during the course of the following 40 detailed description:

In the accompanying drawings, forming a part of this specification, in which similar reference characters designate corresponding parts throughout the several views,

45 Figure 1 is a fragmentary view partly in section, showing the improved adjustable collar in section and various details of its construction.

Fig. 2 is a plan view of the improved 50 adjustable collar showing details thereof

connected to a work supporting table of a shaping machine.

Fig. 3 is a plan view similar to that shown in Fig. 2 and showing the collar adjusted in position to guide a piece of work over a supporting table. 55

Fig. 4 is a cross sectional view taken on the line 4-4 of Fig. 3.

Fig. 5 is a cross sectional view taken on the line 5-5 of Fig. 2. 60

In the drawings, wherein for the purpose of illustration is shown the preferred embodiment of my invention, the letter A designates a shaper machine of any approved type, and having the spindle supports B detachably mounted thereon, and which are provided for the purpose of rotatably receiving a spindle C. A shaper head D of any approved type is provided, for attachment to the spindle C, and adapted to be rotated therewith when some driving means (not shown) is applied to rotate the spindle C by means of the pulley E. A table F is ordinarily provided upon the shaper machine A and receives the collar G, through the horizontal adjusting means H. 65

The shaper machine A, as before stated, may be any approved standard type, and the illustration shown in Fig. 1 is of that type 80 which supports a pair of spindles C upon either side of the machine, by means of the spindle bearings B. The work supporting table F is of any suitable metal, and preferably properly machined to provide a 85 plane work engaging surface 10. The table F is provided with a relatively large circular opening 11 therethrough, and which is provided with an annular shoulder 12, for supporting the adjusting means H, and which 90 will hereinafter be more fully described.

The cutter head D may be of any approved type, and preferably comprises a central shaft 15, which is screw threaded at 16 for the purpose of properly securing 95 the same to the spindle C. A lower collar 17 is mounted over the shaft 15, and normally rests upon the top of the spindle C to project upwardly from the table F in substantially the manner illustrated through 100

out the several views of the drawing. An upper collar 18 is provided, for coöperation with the collar 17, to support any type of cutter 19; and which cutter 19 is ordinarily secured intermediate the collars 17 and 18 by means of a nut 20 clamped upon the upper screw threaded end 21 of the shaft 15 and against the upper surface 22 of the collar 18, substantially as illustrated in Fig. 1.

In this manner the entire cutter head D with the exception of the screw threaded end 16 of the shaft 15 projects upwardly from the table F, and in some instances, the machines can take care of adjustment of the spindle C to secure adjustment of the cutter head D with respect to the table F. The cutter 19 is provided with suitable blades 23, which project outwardly from the outer surfaces of the collars 17 and 18 for the purpose of engaging a piece of work K.

In the general type of shaper machines, it has been the custom to guide the work K directly against the collar 17 and due to vibration of the spindle C, the character of the work resulting therefrom has not, in all instances, reached the required precision. The collar G has therefore been provided, which is adjustably connected directly to the work supporting cable F thus doing away with vibration upon the work K incident to vibration of the spindle C.

The collar G is of tubular formation, and of sufficient diameter to be spaced from the collars 17 and 18 during normal operation of the device. In other words, the interior surface 25 of the collar G is greater in diameter than the diameter of the collar 17. The outer surface 26 of the collar G is of uniform diameter throughout the length of the collar G and when the collar G is attached to the adjusting means H, the outer surface or guiding surface 26 is positioned substantially vertical.

The adjusting means H, preferably comprises a primary disk 30, which is adapted to be disposed directly in the aperture or circular opening 11 in the table F, and rotatably rests upon the annular shoulder 12. The circular opening 11 is concentric with respect to the spindle C and the axis of the cutter head D, and it follows that the outer circumference of the disk 30 will consequently be concentric with the axis of the cutter head D. It is preferred that the disk 30 be only of sufficient depth that the upper surface 31 thereof, lie flush and in the same plane as the flat surface 10 upon the table F. The disk 30 is provided with an eccentric circular opening 32 therein, and which circular opening is provided with a projecting annular shoulder 33. In order to provide sufficient depth between the top of the annular shoulder 33 and top surface 31 of

the disk 30, that portion of the primary disk 30 adjacent the circular opening 32, is relatively thicker than the remaining portion of the disk.

A circular disk 35, which can be conveniently termed the secondary disk, is rotatably disposed within the aperture 32 and is of sufficient depth that when the same rests upon the annular shoulder 33, the top surface 36 will lie exactly flush and in the same plane as the surfaces 10 and 31, of the work supporting table F and primary disk 30 respectively. The secondary disk 35 is provided with an eccentric circular opening 37, and which circular opening is of uniform diameter throughout the depth of the disk 35. This circular aperture or opening 37 is provided to snugly, yet adjustably receive the guide collar G.

In order to clamp the primary adjusting disk 30 to the work supporting table F, the clamping means L is provided. This consists of a locking pin 40 reciprocably disposed within a suitable pocket 41 adjacent the edge of the primary disk 30 and which pocket opens out on to the outer circumference of the disk 30. The locking pin 40 is provided with a beveled pointed end 42, which is first inserted into the pocket 41, and which beveled point is adapted to contact with the beveled point 43 of a clamping screw 44 disposed downwardly from the top of the disk 30. Upon adjustment of the screw 44 within its threaded aperture in the disk 30, the beveled point 43 will contact with the beveled point 42 and feed the pin 40 outwardly into gripping contact with the inner circumference of the aperture 11. Similar clamping means are provided for locking the secondary disk 35 to the primary disk 30; and for locking the secondary disk 35 to the guiding collar G. The operation of the various clamping means L is identical and in all cases, it is preferred that the adjusting screw 44 be disposed below the plane as defined by the work table F. Thus in order to clamp the primary disk, secondary disk, and collar G to the work support table F, it is merely necessary to properly adjust the various screws 44.

In operation, the blades 23 are adjusted to the proper height with respect to the plane of the work table F, and which adjustment forms no part of this invention, as it is provided upon most types of standard shaper machines. However, it is very desirable at times, that that portion of the collar G which projects upwardly from the top surface 10 of the work table F be varied, in order to suit the character of the work K and the particular cutting operation taking place thereon. This adjustment is simply performed by releasing the clamping means L and the collar G can be vertically adjusted in the circular aperture 37, in order to pro-

vide any length of the collar G extending upwardly from the top 10 as defined by the work support table F.

After the knives and more particularly 5 the blades 23 have been adjusted to the required height and the collar G properly adjusted as to the height; it will be necessary to properly adjust the collar G in a horizontal direction in order to properly position the 10 guide surface 26 of the collar G, with respect to the blade 23, in order that said blade may cut the required depth into the work K. It is preferred that in most instances the secondary disk 35 be used for securing relatively large adjustments of the guide collar 15 with respect to the blades 23. This adjustment is of course secured by merely turning the disk 35 within the eccentric opening 32 in the primary disk 30 and which will of course, have the effect of moving certain 20 portions of the guide surface 26 of the collar G, to and from the blades 23. There could, of course, be a micrometer arrangement upon the disk, in order to determine 25 that degree of adjustment which the guide collar G makes with respect to the cutter head D, but for practical purposes, this is not necessary.

In one instance, the guide collar G will be 30 concentrically disposed with respect to the axis of the cutter head D, and in order to determine this position, suitable marks 46 are positioned upon adjacent margins of the primary disk, secondary disk, and work supporting table F, and when these marks are 35 in alinement, with respect to each other, the guide collar G will be exactly concentric with respect to the cutter head D.

The position which the work K is to assume upon the work support table F is determined, and the eccentric or secondary disk 35 is so adjusted within its aperture 32, that the guide surface is adjusted to the proper depth with respect to the blade 23, and upon 45 moving the work K over the table F, in the proper manner; and upon rotation of the cutter head D, the blades 23 will cut to the proper depth, into the work K.

It is preferred that the secondary disk 35 50 be used in most instances for securing the proper adjustment.

However, the primary disk 30 will be found very useful in order to determine fine 55 adjustments where exacting precision is required, and when used in combination with the disk 35 to place the collar G exactly concentric with respect to the cutter head C. Considerable wear will also result, due to 60 sharpening of the blades 43, and it is preferred that the primary adjusting disk 30 be used to compensate for this wear.

From the foregoing, it can be seen that 65 a cutter head has been provided, which when used in combination with the adjustable primary and secondary disks, is capable of per-

forming the exact cutting operations, and when used in connection with the guide collar G will result in accurate work, due to the fact that the guide collar G is independent of the rotary cutter head D.

Various changes in the shape, size and arrangement of parts may be made to the form of the invention herein shown and described, without departing from the spirit of the invention, or the scope of the claims.

I claim:

1. The combination with a shaping machine including a cutter, of a work table, a disk adjustably mounted for eccentric movement in said work supporting table 80 with respect to said cutter, and a work guide collar eccentrically mounted in said disk.

2. The combination with a wood shaper machine including a work supporting table, 85 and a cutting head, of a circular guide collar adjustably mounted in said work supporting table and adapted for eccentric disposition with respect to said cutter head.

3. The combination with a shaping machine including a cutter, of a work supporting table, a disk concentrically mounted in said work supporting table with respect to said cutter and for adjustment thereabout, a second disk eccentrically mounted in said 95 first mentioned disk, and for adjustment therein, and an adjustable work guide collar mounted for eccentric movement in said second mentioned disk.

4. The combination with a wood shaping 100 machine including a work supporting table, and a shaper head, of a disk eccentrically disposed in said work supporting table with respect to said shaper head, and a work guiding means mounted on said disk.

5. The combination with a wood shaping machine including a work supporting table, and a shaper head, of a disk eccentrically disposed in said work supporting table with respect to said shaper head, and a guide 110 collar detachably and adjustably mounted on said disk.

6. The combination with a wood shaping machine including a work supporting table, and a shaper head, of a disk rotatably 115 mounted in said work supporting table about said shaper head, and an eccentric work guiding means rotatably mounted in said disk.

7. The combination with a wood shaping 120 machine including a work supporting table, and a shaper head, of a primary disk rotatably mounted in said work supporting table concentrically with respect to said shaper head, a secondary disk eccentrically and rotatably mounted in said primary disk, and work guiding means mounted upon said secondary disk about said shaper head.

8. The combination with a wood shaping machine including a work supporting table, 130

and a shaper head, of a primary disk rotatably mounted in said work supporting table concentrically with respect to said shaper head, a secondary disk eccentrically and rotatably mounted in said primary disk, and a guide collar adjustably mounted in said secondary disk.

9. A wood shaping machine comprising

in combination a supporting frame, a work table, a cutter head, means rotatably mounting said cutter head with respect to said work table, work guiding means, and means for supporting said guide means upon said table for vertical and lateral adjustment.

WILLIAM R. WHITE.
